UNITED STATES PATENT OFFICE.

PATRICK CURRAN, OF ROMEO, ILLINOIS.

POCKET SECURING DEVICE FOR POCKET-BOOKS, WATCHES, &c.

SPECIFICATION forming part of Letters Patent No. 544,159, dated August 6, 1895.

Application filed May 27, 1895. Serial No. 550,807. (No model.)

To all whom it may concern:

Be it known that I, PATRICK CURRAN, of Romeo, in the county of Will and State of Illinois, have invented a new and useful Pocket 5 Securing Device for Pocket-Books, Watches, &c., of which the following is a full, clear, and exact description.

My invention relates to a device especially adapted for securing a pocket-book, watch, 10 or like article in a pocket, enabling the same to be readily removed from the pocket when necessary, the device being so secured to the pocket that in order to loosen or take out the article secured said article must be pressed 15 downward, thus giving notice to the wearer of an attempt to displace the article.

The invention consists in the novel construction and combination of the several parts, as will be hereinafter fully set forth, and 20 pointed out in the claims.

Reference is to be had to the accompanying drawings, forming a part of this specification, in which similar characters of reference indicate corresponding parts in all the figures.

25 Figure 1 is a perspective view of the improved fastening device, illustrating a pocket-book connected therewith, the pocket-book being shown in dotted lines. Fig. 2 is a plan view of the blank from which the fastening 30 device is made. Fig. 3 is an edge view of the said fastening device, and Fig. 4 is a plan view of the blank of the loop adapted for attachment to the pocket-book and for engagement with the fastening device.

35 In carrying out the invention the fastening device A is preferably made from a strip of steel or like material, which is cut or otherwise manipulated to form virtually two members 10 and 11, each member at its upper 40 edge being provided with a recess 12, forming a tongue 12^a, the tongues of the two members being at opposite sides thereof, so that when the members are brought together these 45 tongues will overlap. At one side of the center of the strip opposing projections or ears 13 are produced, and these ears are formed out of the strip, the member 10 being recessed adjacent to said ears, the recesses being designated as 14, and they are best shown in Fig. 50 2, while the member 11 is cut to form two pins 15, which at their free ends are adapted to engage with the ears 13, a pin being at each

side of said member. Consequently a certain amount of the material is removed from the strip in order to produce the said pins and 55 afford them play and also to complete the formation of the ears 13. The strip of material is bent upon itself below the ears 13, so as to bring the two members 10 and 11 one 60 facing the other, and the tongues are bent downward and inward, the tongue of the member 11 facing the member 10, and vice versa, so that any article that may be placed between the two members 10 and 11 cannot 65 be drawn out therefrom without separating the members and consequently spacing the tongues.

The pocket-book B or similar article is provided, preferably, with a metallic loop 16, and the said loop is shown in Fig. 4, being there 70 shown as made from a strip of metal of suitable width having spurs 17 at its extremities, and these spurs are passed through the back of the pocket-book, the book being preferably reinforced at these points at the inner and outer sides by washers 18 or the equivalents 75 thereof, and the spurs are bent inward, so as to lie close against the inner wall of the back portion of the said book.

When the device is used for holding a watch 80 or like article in the pocket the ring of the watch will be passed down between the two members of the device, assuming the position of the loop 16. (Shown in Fig. 1.) The pins 15 are introduced into one wall of the pocket, 85 and are then carried to an engagement with the upper faces of the ears 13. Consequently the device cannot be removed from the pocket unless the pins are first freed from the ears or is otherwise manipulated to give warning 90 to the person wearing the device, and the pocket-book, watch, or other article adapted to be secured by the device cannot be removed without pressing the members apart sufficiently to permit the loop 16, or the equivalent employed, to pass the downwardly-bent 95 tongues 12^a.

Having thus described my invention, I claim as new and desire to secure by Letters Patent—

100 1. A device for securing pocket books or other articles in a pocket, the same consisting of a strip of metal bent upon itself to form two opposing members, one of said members

being provided with lugs extending from opposite sides, and pins adapted for engagement with the lugs at their free ends, both of the said members having tongues at their upper ends, the said tongues being adapted substantially to interlock, as and for the purpose specified.

2. A device for securing pocket books or other articles in a pocket, the same consisting of a strip of spring material bent upon itself to form opposing and substantially parallel members, the inner member having laterally-extending ears, and pins integral therewith, adapted for engagement at their free ends with said ears, each member being provided at its upper end with downwardly and inwardly extending tongues arranged to interlock, as and for the purpose specified.

3. The combination, with a pocket book or like article provided with a loop secured

thereto, of a device adapted to secure the pocket book or other article in the pocket, said device consisting of a strip of spring material bent upon itself to form substantially parallel members, the inner member having laterally-extending ears at opposite sides above its lower end, and pins adapted at their free ends for engagement with the said ears, being located at opposite sides of the said rear member and adapted to be passed through the material of the pocket, the outer member of the device being adapted to pass through the said loop, and interlocking tongues formed at the upper extremities of the said members of the said fastening device, as and for the purpose set forth.

PATRICK CURRAN.
